UNITED STATES PATENT OFFICE.

JOHN P. MURRAY, OF NEWTON, ILLINOIS.

DESIGN FOR A KITCHEN-CABINET.

SPECIFICATION forming part of Design No. 28,768, dated May 31, 1898.

Application filed February 11, 1898. Serial No. 669,984. Term of patent 14 years.

To all whom it may concern:

Be it known that I, JOHN P. MURRAY, a citizen of the United States, and a resident of Newton, in the county of Jasper and State of Illinois, have invented and produced a new and useful Design for Kitchen-Cabinets; and I do hereby declare that the following is a full, clear, and exact description of the invention, which will enable others skilled in the art to 10 which it appertains to make and use the same, reference being had to the accompanying drawing, which forms a part of this specification.

The invention relates to a design for a kitchen-cabinet; and it consists, essentially, in the novel construction and configuration given thereto, as hereinafter described.

In the accompanying drawing the figure represents a perspective view of a kitchen-cabinet constructed in accordance with my 20 design.

In the said drawing the reference-numeral 1 designates the lower portion of the cabinet, rectangular in shape, forming a receptacle 25 for containing meal, flour, and other material and mounted upon legs 2. This rectangular portion is provided with a number of

vertical and longitudinal strips 3 and 4, forming ornamental panels. In the front of the said receptacle is a door 5, provided with strips 6 at the edges, and also provided with curved strips 7, extending from top to bottom. The numeral 8 designates a dough-board and 9 the covers, provided with knobs 10 for the flour and meal bins. At the rear 35 of said receptacle is a rectangular frame 12, provided with two lower drawers 13 and an upper drawer 14. On top of this frame at each end is a drawer 15. The upper end of said frame is extended upwardly at the rear 40 and has its upper edge inclined from the center toward each end, as shown, thereby giving it an ornamental appearance.

What I claim is—

The design for a kitchen-cabinet, substantially as shown and described.

In testimony that I claim the foregoing as my own I have hereunto affixed my signature in presence of two witnesses.

JOHN P. MURRAY.
